UNITED STATES PATENT OFFICE.

WILLIAM C. KIDDER, OF BUFFALO, NEW YORK.

TONE-TRANSFORMER.

1,362,326.

Specification of Letters Patent. Patented Dec. 14, 1920.

Application filed September 16, 1918. Serial No. 254,297.

To all whom it may concern:

Be it known that I, WILLIAM C. KIDDER, a citizen of the United States, residing at Buffalo, in the county of Erie and State of New York, have invented certain new and useful 5 Improvements in Tone-Transformers; and I do declare the following to be a full, clear, and exact description of the invention, such as will enable others skilled in the art to which it appertains to make and 10 use the same.

My invention relates to improvements in musical instruments, and more particularly to a tone transformer intended for use in numerous kinds of wind instruments to 15 change the tone thereof by making it more "reedy," provision being made however whereby the pitch need not be changed.

With the foregoing object in view, the invention resides in the novel features of construction and unique arrangements of parts 20 as hereinafter fully described, claimed and illustrated.

In Figure 1 of the accompanying drawings is shown a side elevation of the tone transformer applied to the bell of a wind instrument such as a cornet.

Fig. 2 is a view very similar to Fig. 1 but showing the device in section.

Figs. 3 and 4 are transverse sections on the planes of the lines 3-3 and 4-4 respectively of Fig. 1.

Fig. 5 is a transverse section as indicated by the line 5-5 of Fig. 2.

Fig. 6 is a perspective view of the diaphragm and associated parts.

Fig. 7 is a side elevation partly in section showing a different manner of adjustably mounting the device.

In the drawings above briefly described, the numeral 1 designates a supporting member in the form of a sleeve split longitudinally at 2 and having a clamping screw 3 (Figs. 1, 3 and 4) or a clamping nut 4 (Fig. 45) for contracting it around the tubular body 5 of the tone transformer. The supporting member 1 is provided with carrying arms 6 which extend laterally therefrom at 7 and then converge longitudinally, having 50 their ends joined by any suitable means 8. These arms are formed of two strands of wire twisted together and at 9, certain of the convolutions are spread to receive and hold pads 10 of felt or any other preferred 55 material, said pads forming shoes to engage the wall of the sound passage with which

the device is used. The pads 10 are by preference located near the angles of the arms 6, and located between these pads and the connected ends of said arms, are a plurality of elongated plates 11 having openings 12 in their ends, the two strands of wire 13 of each arm being passed outwardly through the openings at one end of the plate and inwardly through those at the other end thereof. The portions of said strands between the openings receive therebetween and grip other pads or shoes 14 by preference formed of cork, although any other yielding material would suffice. The pads 14, in addition to the securing action of the wires 13, are by preference cemented to the plates 11. 60 65 70

By constructing the arms 6 in the manner shown and described, the device may be manufactured easily and inexpensively, yet will be highly efficient and durable, particular emphasis being laid upon the novel manner of securing the pads 10 and 14 in place. 75

The above mentioned tubular body 5 of the tone transformer is open at its inner end and provided at its outer end with an inwardly turned flange 15 against which a diaphragm 16 of oiled paper or any other preferred material bears, a gasket 17 of rubber or the like being positioned against the outer side of said diaphragm and serving to separate the same from a protecting screen 18 of wire fabric. A cap 19 is threaded on the 80 end of the tube 5 in question and is provided with an inwardly extending flange 20 which retains the three parts 16, 17 and 18 in place. Cap 20 is by preference provided with a flared flange 21 serving as a grip by 85 means of which the cap may be removed when required, or adjusted to either tightly or loosely clamp the parts 16, 17 and 18, said grip also serving to adjust the tube 5 longitudinally in the supporting sleeve 1 100 when this sleeve is loosened.

In use, the device is inserted in the bell or in any other suitable part of the wind instrument upon which it is to be used, the shoes 10 and 14 yieldably gripping the wall 105 of the sound passage to retain the device in place. When the instrument is played, the tone thereof will be changed to one greatly desired for some purposes. However, it may be found that the pitch has been altered by 110 the insertion of the device. If so, the contracting means of the sleeve 1 is released and

the tube 5 is moved inwardly or outwardly until the pitch is restored, whereupon said contracting means is again operated to secure the tube in the sleeve. The action of 5 the device is attained by the vibratory currents of air in the bell of the instrument entering the tube 5 and striking the diaphragm 16, which being under tension, vibrates rapidly and thus changes the tone of the 10 instrument as required. In some cases, the device may be constructed for use in a mute for wind instruments, or for insertion in the barrel of any reed instrument.

From the foregoing, taken in connection 15 with the accompanying drawings, it will be obvious that my invention is of comparatively simple and inexpensive nature. Since probably the best results are obtained from the details shown and described, they are 20 by preference followed, but within the scope of the invention as claimed, numerous minor changes may well be made.

I claim:

1. An attachment of the class described 25 comprising a supporting sleeve having arms for yieldably engaging the wall of an instrument sound passage, and a tubular tone transformer received slidably in said sleeve for adjustment longitudinally of said passage, said transformer having a diaphragm 30 at its outer end and being open at its inner end.

2. A tone transformer comprising a tube for reception in a sound passage of a wind 35 instrument, means for holding said tube in such passage and spacing it therefrom to allow the escape of air currents from the passage, and a diaphragm closing the outer end of said tube, the inner end of said tube 40 being open to admit air currents.

3. The combination with a tone transformer, of twisted wire arms extending therefrom, and yielding shoes held between

the convolutions of said arms and adapted for contact with the wall of an instrument 45 sound passage.

4. The combination with a tone transformer, of twisted wire arms extending therefrom, plates having openings through which the wires of said arms pass first outwardly and then inwardly, and yielding shoes on the outer sides of said plates and gripped between the portions of said wires between said openings, said shoes being adapted for contact with the wall of an instrument sound passage.

5. A tone transformer comprising a tube open at one end and means for supporting said tube in a sound passage of an instrument, the other end of said tube having an 60 inwardly turned flange, a diaphragm contacting with the outer side of said flange, a gasket abutting the outer side of said diaphragm, a screen contacting with the outer side of said gasket, and a cap threaded on 65 the last named end of said tube and having an inwardly extending flange for securing said screen, gasket and diaphragm in place.

6. An attachment of the class described, comprising a support for engaging the wall 70 of a sound passage of a wind instrument, and a tone transformer of elongated tubular form mounted on said support and capable bodily of longitudinal adjustment thereon.

7. An attachment of the class described, 75 comprising a support for engaging the wall of the sound passage of a wind instrument, and a tubular tone transformer mounted on said support and capable of longitudinal adjustment thereon and having a diaphragm 80 at its outer end and being open at its inner end.

In testimony whereof I have hereunto set my hand.

WILLIAM C. KIDDER.
